Fig. 5

FIGURE 1 is a front elevational view of a combined Christmas tree holder and stable for a nativity scene showing my new design;

FIGURE 2 is a side elevational view of the design of FIGURE 1;

FIGURE 3 is a top plan view of the design of FIGURE 1;

FIGURE 4 is a perspective view of the design of FIGURE 1; and

FIGURE 5 is a sectional view on a reduced scale along the line V—V of FIGURE 1.

The broken line showing of the tree in FIGURES 1 and 2 is for illustrative purposes only.

The back is substantially plain and unornamented as evidenced by FIGURES 2 and 3 on the drawing.

I claim:

The ornamental design for a combined Christmas tree holder and stable for a nativity scene substantially as shown and described.
